UNITED STATES PATENT OFFICE.

WILLIAM F. WITTICH, OF ERIE, PENNSYLVANIA, ASSIGNOR TO THE WITTICH SUCCESS SHAFT SINKING AND TUNNELLING MACHINE COMPANY, OF ERIE, PENNSYLVANIA, A CORPORATION OF ARIZONA TERRITORY.

SHAFT OR TUNNEL BORING MECHANISM.

No. 902,517.

Specification of Letters Patent.

Patented Oct. 27, 1908.

Application filed December 20, 1907. Serial No. 407,404.

To all whom it may concern:

Be it known that I, WILLIAM F. WITTICH, a citizen of the United States, residing at Erie, in the county of Erie and State of Pennsylvania, have invented certain new and useful Improvements in Shaft or Tunnel Boring Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to mining apparatus and has for its object the construction of mechanism for boring shafts and tunnels and removing the material in liquid form.

The features of my invention are herein-after set forth and explained and illustrated in the accompanying drawings, in which:

Figure 1 is a vertical section of a mine shaft showing my device in elevation therein. Fig. 2 is a like view of a mine shaft showing a vertical section of my device on the line $z-z$ in Fig. 3. Fig. 3 is a top or plan view of my device. Fig. 4 is a transverse section of the same on the line $x-x$ in Fig. 1, looking downward. Fig. 5 is a like section of the same on the line $y-y$ in Fig. 1, looking downward. Fig. 6 shows my device constructed for use in boring a tunnel. Fig. 7 is a side elevation of one of the cutter cylinders. Fig. 8 is a plan view of one of the disks of the cutter cylinders.

In these drawings A, indicates the frame of my device, which frame I secure in the mine shaft by means of supporting screws A¹. In the central part of this frame I secure bearings B B (see Fig. 2) in which bearings I mount a hollow shaft C so that it can have rotative and longitudinal movement. In order to rotate the shaft C, I place thereon a gear-wheel D having trunnions d d mounted in the bearings B¹ B¹ in the frame A. (See Figs. 2 and 4). This gear-wheel D is provided with one or more ribs d¹ in its central opening, (see Fig. 4), which engage one or more longitudinal

grooves e in the shaft C. The power to 50 rotate the gear wheel D and shaft C is generated by an electric motor E which is geared to the wheel D by a pinion e in the usual manner.

Secured on the lower end of the hollow 55 shaft C so as to be driven thereby are one or more arms F F¹ and F² which carry the cutter cylinders G G¹ and G². The relative length of these arms is such that the cutter cylinders G and G¹ will in their revolutions 60 contact with the entire surface of the bottom of the mine shaft. The arm F² carries a cutting cylinder G² mounted on a vertical axle, so that it is adapted to cut out the corner which cannot be cut by the cutter G, 65 and thus keep the wall of the shaft true, and the diameter of the shaft uniform.

The cutting cylinders G, G¹ and G² are each composed of a series of disks g¹ (see Fig. 7) loosely mounted on axles secured in 70 radial positions under the arms F and F¹ as shown in Figs 1 and 2, so that said cylinders may rotate on their axles as the arms F and F¹ revolve. The disks g¹ (see Fig. 8), are provided with teeth or serrations g² which 75 may be of various forms with equally good results. The cutter G² is also constructed of a series of disks having serrated edges as in the case of the other cylinders G and G¹, the only difference being that in the cutter 80 G², the disks g¹ of which it is composed are gradually of less diameter towards the lower end of the cutter, which enables the cutter G² to dress down the side walls and cut out the corner g left by the other cutters. 85

During the process of cutting or boring the mine shaft, water is introduced in plentiful quantity by any means, and from any source desired, (not shown), which reduces the rock powdered up by the cutters to a 90 liquid of greater or less consistency, which is scooped up by the spiral scoop J secured to and revolving with the arms F F¹ and F², and conveyed by reason of the swift rotation thereof into the opening K leading to the inside of the hollow shaft C. Within the hollow shaft C I provide preferably a left-hand conveyer screw and shaft L, (see Fig. 2), 95

which is revolved at great velocity in a direction opposite to the direction of revolution of the shaft C, by means of the motor M and the intermediate bevel gears m and m^1 .
 5 The shaft L is adapted to move longitudinally through the bevel gear m , and is secured against rotation therein by means of a spline l and groove l^1 (see Fig. 3). The conveyer screw and shaft L raises the liquid 10 delivered into the lower end of the shaft C by the scoop J, to the top C^1 of the shaft C whence it overflows down over the cone shaped walls v^1 secured to and revolving with the shaft C, and falls to the bottom 15 of the drum N, and is prevented from escaping through the central opening therein around the shaft C, by means of the cone-shaped walls n ; from the drum N the liquid escapes through the spout n^1 into a bucket O 20 by which it may be raised out of the shaft.

In operation this device is lowered into a mine shaft and the frame thereof securely fastened to the side walls of the shaft by means of the screws A^1 . The shaft C and 25 arms F and cutters secured thereto are then started in rapid revolutions by the motor E and a plentiful supply of water kept constantly running into the shaft. As the cutters G G^1 and G^2 cut away the rock they 30 will settle down by reason of their own gravity, until a satisfactory cut has been made, when the motor E is stopped, and the screws P are turned down until they come in contact with the collar Q on the upper 35 end of the hub of the arms F so as to support the frame A. The supporting screws A^1 are then loosened, and the frame A lowered by means of the screws P until it again rests on the collar Q, when the supporting screws 40 are again turned outward and into the walls of the shaft, which operation is repeated until the shaft has been bored to the required depth.

In Fig. 6 I show a construction of my invention adapted for use in boring tunnels on a horizontal or incline. In this construction the mechanism is substantially the same as that hereinbefore described, the essential difference being that the frame is shorter owing to the fact that the elevating mechanism is omitted. In this construction I provide a frame A^2 which I secure in the tunnel by means of screws A^3 (as illustrated in Figs. 4 and 6). I also provide wheels A^4 50 upon which the frame may be moved forward or backward in the tunnel as desired. In this frame A^2 I mount a hollow shaft C^2 which is driven by means of a motor P and intermediate gears p p^1 (as illustrated in 55 Fig. 6), the shaft C^2 sliding through, and being rotated by said gears by reason of the usual spline and groove, as already described in relation to the shaft-boring machine. In this construction I provide a crowding or

feed-screw R and hand-wheel R^1 , within 65 which the shaft C^2 rotates. This feed-screw is mounted in a screw-threaded opening in the frame A^2 , and, when turned forward presses against the collar C^3 secured around the shaft C^2 , thereby crowding the shaft C^2 forward, and when the screw R is rotated backward it contacts with the collar C^4 and withdraws the shaft C^2 . Upon the inner 70 end of the shaft C^2 I secure the arms F, F^1 and F^2 hereinbefore described.

When this mechanism is used to bore a tunnel having an upward incline the water and powdered material cut away will run out of the tunnel by its own gravity; but when the bore has a downward incline I 80 provide the hub S of the arms F with a spiral scoop J^2 adapted to scoop liquid from the lower wall of the tunnel, and, as the shaft C^2 rotates, convey the scoopful of liquid, through the scoop handle into the 85 opening K shown in Figs. 2 and 5 and into the interior of the hollow shaft C^2 , whence it is carried by means of the screw C^5 to the discharge end thereof and dumped into a car T.

Having thus shown and described my invention so as to enable others to construct and operate the same, what I claim as new and desire to secure by Letters-Patent is:

1. In a shaft or tunnel boring machine the 95 combination of a frame, means to secure said frame to the side walls of the opening being bored, a hollow shaft mounted in said frame, a gear wheel upon said shaft secured against rotation thereon and mounted in said frame, 100 means to rotate said gear-wheel and shaft, cutter arms secured to the end of said shaft, rotative cutters secured to said arms, a conveyer screw within said hollow shaft, and means to convey the material cut-away into 105 the interior of said shaft, substantially as set forth.

2. In a shaft boring machine the combination of a frame, means to secure said frame to the side walls of the shaft, a hollow 110 shaft mounted in said frame so as to allow of rotative and longitudinal movement thereof, means to rotate said shaft, arms secured to the end of said shaft, rotative cutters secured to said arms, means attached to said arms to raise the cut-away material and carry the same into the central opening in the shaft, and means within the 115 shaft to convey such material to the discharge end thereof, substantially as set forth.

3. The combination in a shaft boring machine, of a frame, means to secure said frame to the side walls of the shaft, a hollow shaft mounted in said frame so as to allow of rotative and longitudinal movement, a gear wheel mounted in said frame and upon said shaft so as to rotate in the frame and rotate 125

said shaft, means to rotate said gear-wheel and shaft, arms secured to the end of said shaft, rotative cutters secured to said arms, a spiral scoop secured to said arms adapted to raise liquid material and convey it into said shaft, a conveyer screw mounted in said hollow-shaft, and means to rotate said conveyer screw in a direction opposite to the direction of rotation of said hollow-shaft, substantially as set forth. 10
In testimony whereof I affix my signature, in presence of two witnesses.

WILLIAM F. WITTICH.
